UNITED STATES PATENT OFFICE.

WALTER LANE, OF HOLLAND, MICHIGAN.

AUTOMATIC PLAYER PIANO.

1,422,276.

Specification of Letters Patent. Patented July 11, 1922.

Application filed May 19, 1917. Serial No. 169,670.

To all whom it may concern:

Be it known that I, WALTER LANE, a citizen of the United States, residing at Holland, Michigan, have invented certain new and useful Improvements in Automatic Player Pianos, of which the following is a specification.

This invention relates to improvements in automatic player pianos.

10 The objects of the invention are: First, to provide in a pneumatic player piano an improved tone effect or tone volume regulating means.

Second, to provide improved means where-
15 by a "crash" effect may be produced.

Third, to provide a common means for hastening the force with which the base and treble notes are struck.

Fourth, to provide individual means for
20 regulating the force with which the base and treble notes are struck.

Further objects, and objects relating to structural details, will definitely appear from the detailed description to follow.

25 I accomplish the objects of my invention by the devices and means described in the following specification. The invention is clearly defined and pointed out in the claims.

30 A structure which is a preferred embodiment of my invention is clearly illustrated in the accompanying drawing, forming a part of this specification, in which:

Fig. I is a detail front elevation of a piano player embodying the features of my invention, portions only being illustrated, and these without particular regard to relative size.

Fig. II is a detail plan view of the bellows
40 and regulator parts.

Fig. III is an enlarged detail vertical section on a line corresponding to the broken line 3—3 of Fig. II, showing details of the air connections.

45 Fig. IV is an enlarged detail transverse section on a line corresponding to line 4—4 of Figs. I and III, showing further details of the air connections.

Fig. V is a detail section on a line corresponding to line 5—5 of Fig. III, showing still further details of the air connections.

Fig. VI is an enlarged detail section on a line corresponding to line 6—6 of Figs. I and III, showing details of the air con-
55 nections to the gate box.

Fig. VII is an enlarged detail section on a line corresponding to line 7—7 of Fig. I.

In the drawing similar reference characters refer to similar parts throughout the several views, and the sectional views are 60 taken looking in the direction of the little arrows at the ends of the section lines.

Referring to the drawing, 1 represents the main frame of the instrument and 2 the pedals. These pedals are connected to the 65 bellows or exhausters 3 by suitable means, not illustrated, the usual connections being satisfactory. 4 are reservoirs, the cover of the left hand one being removed to show the valves.

The numeral 5 indicates the suction chest conduits which communicate with passages 6, one of said suction chests controlling the base action, and the other the treble action, in a manner heretofore known. The pas- 70 sages 6 communicate with the exhausters 3 through the regulating pneumatics, designated generally by the numerals 7. The exhausters 3 are on the front of the front wall of the main air chamber 26 and the 80 suction chests are on the rear of the rear wall thereof. The passages 6 communicate with the regulating pneumatics 7 through the boxes or chambers 8. The regulating pneumatics 7 are connected to the gate box 85 9 through the valve chambers 10, there being two ports 11 and 12 between the pneumatics and the valve chambers and a single port 13 between the valve chambers and the gate box. The ports 11 are controlled by valves 14 carried by the diaphragms 15 adapted to be pneumatically actuated. The chambers 16 behind the diaphragms are in communication through the passages 17 and conduits or tubes 18 to valves, designated generally by the numerals 19 in convenient position on the front board 20.

90 When one of the valves 19 is opened the atmospheric pressure will raise the dia-
phragm and close its valve 14, thereby cut-
ting off the passage of air therethrough.
At the same time the vacuum produced will
cause the regulating pneumatic 7 to par-
tially close the valve 21, thereby cutting off
still further the passage of air through the
suction chest to which the regulating pneu-
matic is connected. In this manner a "piano"
effect is produced. The ports 12 are con-
trolled or regulated by the flap valves 21,
which are formed of spring material and 105
110

disposed so that they are normally open. However, when sufficient suction is exerted to actuate the pneumatic this valve is actuated to partially close the port, the pneumatic being provided with an adjustable tappet or valve engaging member 22,—see Fig. III.

The regulating pneumatics are held normally open or extended by the coiled springs 23, shown in Fig. I. These springs are provided with adjusting or tensioning means so that the tension may be adjusted to regulate the action of the regulators. The details of the tensioning means are not shown, as they form no part of the invention, and suitable tensioning means are known in the art.

The gate box 9 is provided with a sliding valve or gate 24, which may be adjusted to cover the port 25. If it is desired to produce a "pianissimo" effect, the gate 24 is partially closed over the port 25, thereby shutting off the passage of the air from the suction chest controlling both the base and treble clef and reducing the force with which the notes are struck. This effect can be further heightened by closing the valve 14.

The port 25 communicates with the main air chamber 26, which is in communication with the bellows 3 and reservoirs 4, as is the usual practice.

The reservoirs are provided with the usual valves 27 and with a port 28 provided with a valve 29. This valve 29 is carried by a spring 30 which holds it normally open but allows it to close under the effect of the extra rush of air due to sudden or forceful pedalling, the result being that a loud or a "crash" effect is secured, owing to the sudden increase in vacuum thus resulting. The strength of spring 30 is such that it yields to the suction or air movement and is thus adapted to close under the conditions created. The spring 30 is adjustable by means of the screw 31, so that the resistance to closing of the valve may be regulated.

By the arrangement above described, the force with which the notes in either the base or treble action or in both are struck can be regulated to any desired degree. For instance when it is desired to secure a piano effect in the base action, the valve 14 controlling the base action is closed, and similarly, when it is desired to produce a similar effect in the treble action, the valve 14 controlling the treble action is closed. When it is desired to obtain this effect in both of the actions at the same time, the valve 14 may be closed or the port 25 may be partially closed by the gate 24. Varying degrees of softness may be produced by the combined action of the valve 14 and by positioning the gate 24 in various positions relative to the port 25.

When it is desired to produce a forte effect, the exhausters 3 are actuated sufficiently vigorously to close the valve 27, but when it is desired to secure a "crash" effect the exhausters 3 are actuated vigorously enough to close not only the valve 27 but also the valve 29. The reservoirs 4 are thereby cut off from the exhausters and the degree of exhaustion in the suction chest is increased to such an extent as to produce the desired effect. It should be noted that this effect can be regulated and softened in either the base or treble action by closing the corresponding valve 14, and it can also be reduced in both actions simultaneously by the proper manipulation of the gate 24.

With the parts thus arranged and connected, the regulators 7 are disposed so that the connection to the exhaust chamber 26 is short and direct and they are positioned so that the operating connections for these regulators are conveniently disposed.

I have illustrated and described my improvements in the form in which I have embodied the same in practice. I have not attempted to illustrate or describe any modifications or other adaptations thereof, as I believe the disclosure made will enable those skilled in the art to which my invention relates to embody or adapt the same as may be desired.

Having thus described my invention, what I claim as new and desire to secure by Letters Patent, is:

1. In a structure of the class described, the combination with the exhausters, of reservoirs communicating therewith and having a plurality of ports provided with normally open spring supported valves adapted to be closed by sudden actuation of said exhausters and at different stresses, means for adjusting said springs, a gate box in communication with said exhausters, a pair of suction chest regulating pneumatics, valve chambers between said regulating pneumatics and gate box communicating with said pneumatics through pairs of ports, valves for one port of each pair provided with manually controlled actuating means, and regulating valves for the other ports controlled by said regulating pneumatics and adjustable tappets on said pneumatics for said valves.

2. In a structure of the class described, the combination with the exhausters, of reservoirs communicating therewith and having ports provided with normally open spring supported valves adapted to be closed by sudden actuation of said exhausters, means for adjusting said valve springs, a gate box in communication with said exhausters, a pair of suction chest regulating pneumatics, valve chambers between said regulating pneumatics and gate box communicating with said pneumatics through pairs of ports, valves for one port of each pair provided

with manually controlled actuating means, and regulating valves for the other ports controlled by said regulating pneumatics.

3. In a structure of the class described, 5 the combination with the exhausters, of reservoirs communicating therewith and having ports provided with normally open spring supported valves adapted to be closed by sudden actuation of said exhausters, a 10 gate box in communication with said exhausters, a pair of suction chest regulating pneumatics, valve chambers between said regulating pneumatics and gate box communicating with said pneumatics 15 through pairs of ports, valves for one port of each pair provided with manually controlled actuating means, and regulating valves for the other ports controlled by said regulating pneumatics.

20 4. In a structure of the class described, the combination with the exhausters, of reservoirs communicating therewith and having ports provided with normally open spring supported valves adapted to be closed by 25 sudden actuation of said exhausters, a gate box in communication with said exhausters, a pair of suction chest regulating pneumatics, valve chambers between said regulating pneumatics and gate box communicating 30 with said pneumatics through pairs of ports, valves for one port of each pair provided with manually controlled actuating means, and regulating valves for the other ports controlled by said regulating pneumatics and provided with adjustable tappets.

5. In a structure of the class described, the combination with the exhausters, of reservoirs communicating therewith, a gate box 40 in communication with said exhausters, a pair of suction chest regulating pneumatics communicating with said gate box through pairs of ports, valves for one port of each pair provided with manually controlled 45 pneumatic actuating means, and regulating valves for the other ports controlled by said regulating pneumatics and provided with adjustable tappets.

6. In a structure of the class described, 50 the combination with the exhausters, of res-

ervoirs communicating therewith and having ports provided with normally open spring supported valves adapted to be closed by sudden actuation of said exhausters, a gate box in communication with said exhausters, 55 manually actuated means for controlling the passage of air through said gate box, a pair of suction chest regulating pneumatics, valve chambers between said regulating pneumatics and gate box communicating with 60 said pneumatics through pairs of ports, valves for one port of each pair provided with operation controlled actuating means, and regulating valves for the other ports controlled by said regulating pneumatics. 65

7. In a structure of the class described, the combination with the exhausters, of reservoirs communicating therewith and having ports provided with normally open spring supported valves, a pair of suction chest regulating pneumatics, valve chambers between said regulating pneumatics and said exhausters communicating with said pneumatics through pairs of ports, valves for one port of each pair provided with operation controlled actuating means, and regulating valves for the other ports controlled by said regulating pneumatics. 75

8. In a structure of the class described, the combination with the exhaust means of reservoirs communicating therewith, a pair of suction chests, means for regulating the suction in said suction chests comprising a suction regulating pneumatic, and manually controlled means for regulating the suction in each of said suction chests individually, and separate manually controlled means for regulating the suction in both of said suction chests, the first and last manually controlled regulating means being arranged in series whereby the latter means can control the action of the other. 90

In witness whereof, I have hereunto set my hand and seal in the presence of two witnesses.
